UNITED STATES PATENT OFFICE.

REUBEN HALEY, OF BEAVER, PENNSYLVANIA, ASSIGNOR TO UNITED STATES GLASS COMPANY, OF PITTSBURGH, PENNSYLVANIA, A CORPORATION OF PENNSYLVANIA.

DESIGN FOR A PITCHER.

45,230.

Specification for Design.

Patented Feb. 10, 1914.

Application filed December 4, 1913. Serial No. 804,785. Term of patent 7 years.

To all whom it may concern:

Be it known that I, REUBEN HALEY, a citizen of the United States, and residing at Beaver, in the county of Beaver and State of Pennsylvania, have invented a certain new, original, and ornamental Design for a Pitcher, of which the following is a specification, reference being had to the drawing forming a part thereof, in which the pitcher is illustrated in side elevation.

I claim:

The ornamental design for a pitcher, substantially as shown.

REUBEN HALEY.

Witnesses:

HARNEY WILSON,
WILLIAM R. NICKEL.
